ABSTRACT: Apparatus for freeing the tube of a muffler body from a tailpipe that has an end point normally positioned inside the tube at a predetermined location along the axis of the tube. The preferred form of the apparatus comprises means for structurally weakening the tube along a line located in the tube. The line has a first portion that extends toward the body of the muffler and a second portion that extends around at least half the circumference of the tube at a position adjacent the predetermined location. Means are also provided for separating the tube along the line, so that the tailpipe may be conveniently removed from the tube.

REMOVABLE TAILPIPE CONNECTION

BACKGROUND OF THE INVENTION

This invention relates to mufflers and is more specifically related to apparatus for freeing a muffler from an attached tailpipe.

Automobile mechanics and all persons who have ever attempted to remove a wornout muffler from an automobile recognize that the task of separating the muffler from the tailpipe of the vehicle is extremely difficult and time-consuming. Typical automotive mufflers are provided with an inlet tube that is fitted over a tailpipe connected to the vehicular engine and an exit tube that is fitted over another tailpipe extending to the rear of the vehicle. In order to replace a wornout muffler, each of these tailpipes must be disconnected from its respective muffler tube. If the muffler and tailpipe have been used for any substantial period of time, they are normally corroded by the vapors emitted from the vehicle engine. As a result, the tailpipes and tubes are generally fused together.

In order to disconnect the tubes and tailpipes, automobile mechanics conventionally employ a pneumatic chisel that splits one of the muffler tubes in several places in order to free its associated tailpipe. When the tube has been partially freed in the foregoing manner, it is normally pounded with a hammer in order to completely disconnect it from the tailpipe. Naturally, the foregoing procedure requires considerable time and physical strength on the part of the mechanic. Moreover, by using this procedure, it is difficult if not impossible to remove the muffler without severely damaging the tailpipe. As a result, a wornout muffler frequently necessitates the replacement of a tailpipe as well. When the muffler is freed from one of its tailpipes, it is generally rotated and twisted to free it from the other tailpipe. This process is also difficult and requires considerable strength on the part of the mechanic.

Various methods designed to facilitate the disconnection of a muffler from its associated tailpipes have been attempted in the past, but each has exhibited deficiencies that have limited its overall usefulness. For example, one prior art method described in U.S. Pat. No. 2,476,566 (Scott - July 19, 1949) suggests the use of a grooved strip that is inserted between a muffler tube and tailpipe. The grooved strip is then rolled toward the muffler, thereby tearing away a portion of the muffler tube. This approach requires a number of parts that are relatively difficult to assemble, and does not completely free the muffler tube from its tailpipe.

Accordingly, it is a primary object of the present invention to provide an improved apparatus for disconnecting a muffler tube and an associated tailpipe.

It is yet another object of the present invention to provide such apparatus whereby the muffler tube and tailpipe can be completely disconnected without the use of expensive tools or additional muffler parts.

It is still another object of the present invention to provide a muffler tube that is structurally weakened along a line which is shaped so that the muffler tube and tailpipe may be completely separated by merely severing the tube along the line.

Yet another object of the present invention is to provide improved means for facilitating the separation of a muffler tube along an indentation line located on a surface of the tube, said means being formed so that it may be fabricated as an integral part of the tube.

Still another object of the present invention is to provide improved apparatus for removing a muffler from a tailpipe in which a mechanic needs to use his hands on only one side of the muffler, thereby allowing the muffler to be removed without interference from adjacent vehicular parts.

SUMMARY OF THE INVENTION

In order to achieve the foregoing objects, advantages, and features, the present invention, in principal aspect, comprises improved apparatus for freeing the tube of a muffler from a tailpipe that has an end point normally positioned inside the tube at a predetermined location along the axis of the tube.

The improved apparatus preferably comprises means for structurally weakening the tube along a line having a first portion that extends toward the body of the muffler and a second portion that extends around at least half the circumference of the tube at a position adjacent the end point of the tailpipe (i.e., at a position adjacent the predetermined location). The improved apparatus also comprises means connected to the tube, such as a tab, for facilitating the separation of the tube along the line.

The advantages of the above-described apparatus are at once apparent. By merely pulling the tab, the muffler tube can be separated along the line, thereby disconnecting a large portion of the tube from the tailpipe. Since the line extends around at least half the circumference of the tube, the tailpipe may then be easily removed by merely pushing or pulling it away from the unsevered portion of the tube. This procedure requires relatively little energy, and may be achieved without any damage to the tailpipe.

According to another feature of the invention, the tab may be provided with a hole that will accept a rodlike tool. The tool can be used to give a mechanic additional leverage for separating the tube along the line.

By properly placing the tab and the line in relationship to a vehicle connected to the muffler, the entire severing operation may be carried out on the side of the muffler away from the vehicle, so that the mechanic's work will not be impeded by the close proximity of the chassis and muffler. By using the described apparatus, a mechanic may conveniently remove a tailpipe from a muffler in a matter of seconds without the use of expensive tools and without damaging the tailpipe. As a result, muffler removal can be safely achieved with a degree of convenience and ease heretofore unattainable. DESCRIPTION OF THE DRAWING

These and other objects, advantages, and features of the present invention will hereinafter appear for purposes of illustration, but not of limitation, in connection with the accompanying drawing, in which like numbers refer to like parts throughout, and in which:

FIG. 1 is a perspective, fragmentary, view of a preferred form of the present invention shown in relationship to a tailpipe, a portion of a vehicle chassis, and an exemplary rodlike tool used in connection therewith;

FIG. 2 is a top plan, fragmentary view of the preferred form of the invention shown in FIG. 1 with the tailpipe removed;

FIG. 3 is a top plan, fragmentary view of the apparatus shown in FIG. 1 with the tube thereof partially separated along the indentation line;

FIG. 4 is a top plan, fragmentary view of another form of apparatus made in accordance with the present invention; and

FIG. 5 is an enlarged, front elevational, fragmentary view showing the manner in which the tab portion of the apparatus shown in FIG. 4 may be used.

DESCRIPTION OF THE PREFERRED EMBODIMENTS

Referring to FIGS. 1-3, the preferred form of the present invention is generally used in connection with a conventional vehicular muffler 8 that comprises a metal body portion 10, a rear wall 12, and a hollow, metal, exit tube 14. The muffler body also terminates in a front wall and a hollow inlet tube (not shown) that is connected through a tailpipe to an internal combustion engine. The body of the muffler contains baffles and insulation that reduce the level of sound emitted by the engine in a well-known manner.

Exit tube 14 comprises a first end 16 that is connected to wall 12 and a second end 18 that is displaced from the muffler body.

A metal tailpipe 20 having an end point 22 is located inside exit tube 14 in the position shown along the axis 23 of the tube.

The preferred form of the present invention used in connection with the above-described apparatus basically comprises depressions 24, 25, a discontinuous indentation line 26 that is

formed on the outer surface of tube 14, and a tab 32 that provides a means for facilitating the separation of the tube along the indentation line.

More specifically, indentation line 26 comprises a means for structurally weakening tube 14 so that the tube may be easily separated along the line. Of course, means other than an indentation line may be used to achieve the same purpose. For example, the tube may be formed from separate parts that are spot welded along the desired line. Indentation line 26 comprises a first portion 28 that extends between points A and B on the outer surface of tube 14, and a second portion 30 that extends between points B and C on the outer surface of tube 14. The second portion of the indentation line is preferably located between the end 22 of tailpipe 20 and the body of muffler in an area of the tube bounded by end 22 of tailpipe 20 and the body of muffler 8. Depressions 24, 25 are stamped into tube 14 in order to prevent end point 22 of tailpipe 20 from extending into the tube beyond the second portion of line 26. Of course, other means may be employed to position the tailpipe, as long as end point 22 does not extend beyond portion 30 to any substantial extent. It should also be noted that the second portion of the indentation line must extend around at least half the circumference of the tube in order to adequately free the tailpipe. The indentation line may be formed by merely stamping spaced impressions into the surface of the tube to an appropriate depth. The optimum depth depends on the thickness of the tube and the type of material from which it is fabricated.

Tab 32 comprises a suitable piece of metal that defines an orifice 34 adapted to accept a rodlike tool 36 having a handle 38. As shown in FIG. 2, the tab is connected at end 18 of the tube adjacent the first portion of the indentation line.

As shown in FIG. 1, the tab is arranged on the portion of the tube adjacent an exemplary underpanel of a vehicular chassis 39. Moreover, the second portion of the indentation line is substantially located on the portion of the tube opposite the vehicular chassis.

In order to remove muffler 8 from tailpipe 20, tool 36 is inserted in orifice 34 in the manner shown in FIG. 1. Thereafter, the tool is turned in a counterclockwise direction (as viewed in FIG. 1) so that the tube is separated along indentation line 26 in the manner shown in FIG. 3. The tool is normally turned around the tube until the entire first and second portions of the indentation line have been separated from the tube (i.e., until the tube has been separated around at least half its circumference). As the tool is turned, the portion of the tube remaining attached to the tailpipe (generally indicated by the number 31) stabilizes the tube and prevents it from turning.

Thereafter, the tailpipe 20 may be easily removed by merely pushing or pulling it in a direction away from chassis 39. By arranging the indentation line and tab as shown, the handle of tool 36, as well as the mechanic's hand, are always located on the side of the tube opposite the vehicle chassis. As a result, there is little or no danger that the removal of the muffler will be interfered with by adjacent parts of the vehicle. As previously explained, the entire portion of the muffler connected to tailpipe 20 may be removed in a matter of seconds by the use of the apparatus described herein.

Another embodiment of the invention is illustrated in FIGS. 4 and 5. As shown in the drawing, this embodiment of the invention comprises a continuous indentation line 40 that is located on the inner surface 41 of a tube 14 that is made from any suitable material. More specifically, indentation line 40

comprises a first portion 42 that extends from point D to point E, and a second portion 44 that extends from point E to point F. The relative positions of indentation line 40 and a tailpipe fitted inside tube 14 are the same as the analogous relationship described in connection with FIGS. 1-3. The depth to which line 40 is impressed in surface 41 depends on the thickness and composition of tube 14.

In the second embodiment the invention, tube 14 comprises a tab portion 46 that defines an orifice 48. The tab portion is 10 integrally formed with the tube and is further defined by a slot 50 that is stamped through the tube in the position shown. It should be noted that tube 14 (FIGS. 4 and 5) can be entirely formed from a single piece of material by inexpensive stamping processes, thereby insuring an economical method of manufacture.

In order to remove a tailpipe inserted in the tube shown in FIGS. 4 and 5, a screwdriver, chisel, or like implement is inserted between the tube and tailpipe in order to raise tab portion 46 in the manner indicated in FIG. 5. Thereafter, a tool, 20 such as tool 36, may be inserted in orifice 48. The tube may then be separated along indentation line 40 in the manner previously described.

Those skilled in the art will appreciate that the inlet tube of muffler 8 may be fitted with apparatus analogous to the indentation lines and tabs shown in the drawing in order to remove the muffler from the tailpipe inserted therein. Moreover, the indentation line and tab may be placed on the tailpipe in the event that it is fitted over the muffler tube. Those skilled in the art will recognize that the particular embodiments of the invention described herein may be altered and modified in additional ways without departing from the true spirit and scope of the invention.

I claim

1. In a muffler comprising a body and a hollow rigid tube having one end connected to the body and a second end displaced therefrom, improved apparatus for freeing the tube from a tailpipe having an end point normally positioned inside the tube at a predetermined location along the axis of the tube, said apparatus comprising,

a line of structural weakening along the tube, said line having a first portion that extends toward the body and a second portion that extends around at least half the circumference of the tube substantially in the area of the tube bounded by the predetermined location and the muffler body; and second means securely connected to the tube for facilitating the separation of the tube along the first and second portions of the line, said second means comprising a tab connected to the second end of the tube adjacent the first portion of the line, said tab defining means to which a tool may be connected to separate the tube along the line.

2. Apparatus, as claimed in claim 1, wherein said tab is formed as an integral part of said tube and wherein said tube defines a slot located adjacent said tab.

3. Apparatus, as claimed in claim 1, and further comprising third means forming a part of the tube for preventing the end point of said tailpipe from extending into said tube beyond the second portion of said line, so that the second portion of said line lies between the third means and said muffler body.

4. Apparatus, as claimed in claim 1, wherein said second portion substantially lies in a single-plane perpendicular to said axis.
